UNITED STATES PATENT OFFICE.

WILBUR MILLER, OF EAGLE ROCK, CALIFORNIA.

CAP.

1,178,091.

Specification of Letters Patent.

Patented Apr. 4, 1916.

Application filed January 26, 1916. Serial No. 74,436.

To all whom it may concern:

Be it known that I, WILBUR MILLER, a citizen of the United States, residing at Eagle Rock, in the county of Los Angeles and State of California, have invented certain new and useful Improvements in Caps, of which the following is a specification, reference being had to the accompanying drawings.

10 This invention relates to certain improvements in caps for inflating valves and it is an object of the invention to provide a device of this general character having novel and improved means whereby the same may 15 be readily applied to or removed from operative position, and whereby the same when in applied position is effectively held against accidental displacement.

The invention consists in the details of 20 construction and in the combination and arrangement of the several parts of my improved cap whereby certain important advantages are attained and the device is rendered simpler, less expensive and otherwise 25 more convenient and advantageous for use, all as will be hereinafter more fully set forth.

The novel features of the invention will be hereinafter definitely claimed.

30 In order that my invention may be the better understood, I will now proceed to describe the same with reference to the accompanying drawings, wherein—

Figure 1 is a view partly in elevation and 35 partly in section illustrating an inflating valve constructed in accordance with an embodiment of my invention; Fig. 2 is a sectional view taken substantially on the line 2—2 of Fig. 1; Fig. 3 is a view in outer end 40 elevation of the cap as herein embodied; Fig. 4 is a view in plan of the annular member as herein employed; and Fig. 5 is a view in outer end elevation of the bushing as herein disclosed.

45 As disclosed in the accompanying drawings, 1 denotes the hollow stem of any ordinary or preferred type of inflating valve adapted to be in communication with an inflatable tire in a conventional manner and 50 disposed through the rim R of the wheel, and the periphery of the stem 1 is threaded, as at 2, and has its face at diametrically opposed points flattened, as at 3, for a purpose to be hereinafter more particularly referred to. The stem has also applied thereto a 55 washer 4 of leather or any desired material

adapted to engage the inner wall of the rim R to hold out of contact therewith the sleeve or collar 5, threaded upon the stem 1 and having the opposite ends of its bore enlarged as at 6, to afford the chambers a and b, the chamber a receiving the outer portion of the washer 4, while the second chamber b has positioned therein the expansible member 7, herein disclosed as a conventional coil 60 spring surrounding the stem 1 with its outer end bearing against the annular member 8, the bore of which is provided with the straight portions 9 coacting with the flattened faces 3 of the stem 1, whereby said 65 member 8 is held against rotation independently of the stem 1 but is capable of movement longitudinally thereof.

The inner wall of the chamber b is 70 threaded to afford detachable engagement 75 therewith of the bushing 10 of a diameter in excess of the maximum diameter of the stem 1 and into which the annular member 8 is normally maintained under the influence of the expansible member 7, the outward 80 movement of the annular member 8 being limited by the equidistantly spaced inwardly disposed fingers 11 carried by the outer face of the bushing 10 and partially 85 overlying the bore thereof.

C denotes an elongated dust cap having its outer end closed and adapted to be inserted over the outer end portion of the stem 1, and the inner or open end of the cap C is provided with the outwardly directed annular flange 12 provided with the equidistantly spaced notches 14 through which the inturned fingers 11 are adapted to pass when the inner end of the cap C is forced inwardly within the bushing 10 against deten- 90 tation of the expansible member 7, and 95 whereby said cap is effectively maintained in applied position upon a partial axial rotation being imparted to the cap C.

In order to effectively lock the cap C in 100 applied position, I find it particularly desirable to have the inner faces of the annular flange 12 at the inner end of the cap C at points intermediate the notches 14, provided with the recesses or pockets 15 to receive said inturned fingers 11, whereby the cap C is locked against axial rotation, and 105 it will be at once self-evident that the fingers 11 are held seated in the recesses 15 under the influence of the expansible mem- 110 ber 7.

It is thought to be clearly apparent to

2
 those skilled in the art to which my invention appertains, that the cap C may be readily and effectively applied to or removed from operative position relative to the stem 5 1 and that said cap is effectively locked in applied position. It will also be self-evident that the possibility of the cap C working loose is eliminated.

From the foregoing description, it is 10 thought to be obvious that a cap constructed in accordance with my invention is of an extremely simple and comparatively inexpensive nature and is particularly well adapted for use by reason of the convenience and 15 facility with which it may be assembled, and it will also be obvious that my invention is susceptible of some change and modification without material departure from the principles and spirit thereof and for this reason 20 I do not wish to be understood as limiting myself to the precise arrangement and formation of the several parts herein shown in carrying out my invention in practice.

I claim:

25 In combination with a valve stem having its periphery threaded and provided with a flattened face extending longitudinally thereof, a collar threaded upon the stem and having the outer end of its bore enlarged to 30 afford a chamber surrounding the stem, a bushing detachably engaged within the enlarged bore of the collar, said bushing having its bore of a diameter in excess of the maximum diameter of the stem and pro-

vided with inwardly disposed fingers adjacent its outer face, an annular member positioned within the chamber afforded by the enlarged portion of the bore of the collar and the bushing and slidably engaged with the stem, the bore of said annular member 40 being provided with a straight edge coacting with the flattened face of the stem whereby said annular member is held against rotation independently of the stem, an expandible member within the chamber afforded by the enlarged end of the bore of the collar and the coacting bushing and constantly urging the annular member outwardly, said fingers serving to limit the outward movement of the annular member, and 45 a cap for the stem closed at one end and having its open end provided with an outstanding annular flange provided with notches through which the fingers of the bushing are adapted to pass so that the 50 flange of the cap may be engaged beneath the fingers of the bushing upon axial rotation of the cap, the annular flange of the cap being provided in its outer face intermediate the notches with recesses to receive 55 the fingers of the bushing to hold the cap against rotation when in operative position.

In testimony whereof I hereunto affix my signature in the presence of two witnesses.

WILBUR MILLER.

Witnesses:

JOHN F. POOLE,
GEORGE G. FITTERS.
